UNITED STATES PATENT OFFICE.

EZRA E. CLARK, OF NEWTONVILLE, MASSACHUSETTS.

RETARDING DEVICE FOR ALARM CHECK VALVES.

Application filed September 24, 1923. Serial No. 664,412.

To all whom it may concern:

Be it known that I, EZRA E. CLARK, a citizen of the United States, and resident of Newtonville, county of Middlesex, State of Massachusetts, have invented an Improvement in Retarding Devices for Alarm Check Valves, of which the following description, in connection with the accompanying drawing, is a specification, like characters on the drawing representing like parts.

This invention relates to alarm check valves such as are used in sprinkler systems and particularly to a retarding device for retarding the opening movement of the alarm valve so as to preclude the possibility of the alarm valve opening when the main check valve lifts slightly due to a temporary water surge or to a momentary difference in pressure between the two sides of the check valve.

One feature of the invention relates to an alarm valve operative device which comprises an expandible chamber having a movable wall, one side of which is subjected at all times to the pressure on the delivery side of the check valve and the other side of which is subjected at all times to the pressure on the inlet side of the check valve. This expandible chamber with its movable wall may be in the form of a bellows-like device which is subjected interiorly to the pressure on one side of the main check valve and is subjected exteriorly to the pressure on the delivery side of said check valve. The bellows-like device has associated with it a retarding device which retards the operative movement thereof and which is so constructed that the alarm valve will not be open until the difference in pressure on opposite sides of the main check valve has been maintained for a predetermined length of time.

In order to give an understanding of the invention I have illustrated in the drawings a selected embodiment thereof which will now be described after which the novel features will be pointed out in the appended claims.

In the drawings Fig. 1 shows in vertical section a retarding device embodying my invention;

Fig. 2 is a fragmentary view showing the auxiliary check valve in open position.

1 indicates a check valve casing which is situated in the supply pipe of a sprinkler system, and is provided with a water-way

2 therethrough which is controlled by a weighted check valve 3, all as usual in devices of this sort. The check valve 3 is pivotally mounted at 4 and seats upon a 60 valve seat 5.

The check valve is herein shown as having a port 6 therethrough which is controlled by an auxiliary check valve 8 having a stem extended through said port and provided at 65 its lower end with a head 7 in the form of a valve adapted to close the lower end of the port 6. This check valve is pivotally connected to a lever 9 which in turn is pivoted to the main valve at 10, the end 11 of the 70 lever extending beyond the main valve and co-operating with a stop projection 12 formed on the casing.

When the main valve 3 is closed and pressure conditions are normal within the valve 75 casing 1 the valve 8 will be closed to its seat by gravity and the end 11 of the lever will be situated slightly above the stop shoulder 12 as shown in Fig. 1. If, for any reason, there is an increase of pressure on 80 the inlet side of the valve 3 due to water surge or some other cause the valve 8 will be lifted from its seat, as shown in Fig. 2, thus allowing a small flow of water from the inlet side to the delivery side of the main 85 valve through the valve port 6. The opening movement of the valve 8 is limited by the end of the lever 11 engaging the stop projection 12. The opening of the auxiliary valve 8 allows a small flow of water through 90 the main check valve, which will be sufficient to compensate for such temporary water surges as ordinarily occur and thus with this invention such temporary water surges do not cause the main check valve 3 95 to be lifted from its seat.

When the temporary water surge has ceased and the pressure on both sides of the main check has been equalized, the auxiliary valve 8 will close thus preventing a reverse 100 flow. If the temporary water surge is of sufficient proportions so that the water flow cannot be accommodated by the port 6 then the main check valve 3 will be lifted and as it lifts from its seat the valve 7 will automatically close the lower end of the port 6 105 thus compelling all the water to pass through the opening caused by the lifting of the main check valve. The main check valve 3 will, therefore, remain closed until the flow 110 of water exceeds that which can be accommodated by the port 6 and then said main

check valve will open to a point which is at least sufficient to accommodate the amount of water which could flow through the bypass port 6.

5 The advantage of this construction is that it ensures that the minimum amount which the main check valve 3 will open, will be such as to permit a sufficient flow of water over the valve seat to keep the latter free 10 from sediment or foreign matter which might collect thereon if the check valve was allowed to merely crack open slightly by a temporary water surge.

My improved retarding device comprises 15 an expansible member having a movable wall which is at all times subjected on one side to the pressure on the inlet side of the check valve 3 and on the other side to the pressure on the delivery side of said check valve so 20 that a difference in the pressures at the inlet and delivery sides of the check valve will produce a difference in pressure on opposite sides of said movable wall to cause an expansion or contraction of the expansible 25 chamber.

Connections are provided for opening the alarm valve by the expansible movement of the expansible chamber and means are also provided for retarding the alarm-valve- 30 opening movement of the expansible chamber so that the alarm will not be opened until the difference in pressure on opposite sides of the main check valve has continued for a predetermined length of time.

35 Associated with the valve casing 1 is another casing 13 having two chambers 14 and 15 therein. The chamber 14 communicates with the water-way on the delivery side of the check valve 3 through a duct or 40 passage 16 and the chamber 15 communicates with the water-way on the inlet side of said check valve through a duct or passage 17.

Each of the passages 16 and 17 is provided 45 with a strainer 50, the purpose of said strainers being to prevent any dirt or foreign substance from entering the chambers 14 and 15.

The expansible chamber, to which reference has been made is herein shown as a bellows-like device 18 which is situated in the 50 chamber 14 and one end of which is secured to the partition 19 dividing said chambers. This partition has an opening 20 therein which communicates with the interior of the 55 bellows-like device 18 so that the head or wall 21 thereof is subjected on its upper side to the pressure in the chamber 14 and on its lower side to the pressure in the chamber 15.

60 The chamber 15 has a port 22 leading therefrom which communicates with a pipe 23 leading to the alarm mechanism. This port 22 is normally closed by an alarm valve indicated generally at 24. I will preferably use for this purpose a nearly balanced valve, 65 that herein shown comprising a hollow valve

stem 25, having two valve members 26 and 27, thereon, the valve 26 seating on a valve seat 28 and the valve 27 seating on a valve seat 29. The valve member 27 is enclosed in a chamber 30 which communicates with the 70 port 22 through the bore formed in the valve stem 25. With this arrangement the pressure against the valve 26, tending to hold it to its seat, will be nearly counterbalanced by the pressure against the valve 27, tending to 75 open it, thus producing a nearly balanced valve which can be easily opened by a slight excess of pressure in the chamber 15.

This alarm valve is connected to the head 80 21 of the bellows-like arrangement by suitable means which are arranged so that when the bellows expands by reason of a reduction of pressure in the chamber 14 on the delivery side of the check valve, said alarm 85 valve will be opened.

For this purpose I have provided a lever 31 which is pivoted at 32 and is connected at 33 to the valve stem 25, the free end of the lever 34 being forked and embracing a stem or rod 35 which is secured to and 90 depends from the head 21. This rod 35 is provided with a pin 36 arranged to engage the forked end of the lever when the head 21 is raised, thereby raising the lever 31 and opening the alarm valve. It is important that the alarm valve should not be opened by a pressure difference of short duration in the chambers 14 and 15 such as would result from water hammer or a surging 95 movement of the water in the supply pipe, for otherwise a false alarm might be given. When a sprinkler head gives way and there is necessity for an alarm there will be a continued pressure difference in the 100 chambers 14 and 15, and the apparatus herein shown is designed to differentiate between a pressure difference of short duration and one of long duration.

The pin 36 is shown as situated some distance below the forked end 34 of the lever 31 110 when the parts are in the normal position shown in the drawing, and therefore, the initial upward movement of the head 21 will not actuate the lever 31, but, on the other hand, said lever will only be actuated 115 to open the alarm valve when the head 21 has an upward movement of a greater extent than that necessary to bring the pin 36 against the forked end 34 of the lever 31.

A retarding device is employed to retard 120 the upward movement of the head 21, thereby to insure that said head will not have its full operative movement unless the pressure difference in the chambers 14 and 15 continues for a predetermined time interval.

The stem 35 is shown as having rack teeth 125 37 which mesh with a gear 38 journalled on a shaft 39 that extends transversely of the casing 13. The rack is held in engagement with the gear by a guide roller 40 that en-

gages the back face of the stem. The gear 38 has rigid therewith a gear sector 41 which is connected through a gear train to a retarding paddle 42 that is mounted on a shaft 5. 43. This gear train is a speed-increasing one and it comprises a small gear 44 meshing with the gear segment 41, which small gear is connected to a larger gear 45 that in turn meshes with a smaller gear 46 rigid with the 10 retarding fan 42. The gears 44 and 45 are connected by a pawl and ratchet mechanism comprising a spring-pressed pawl 47 pivoted on the gear 45 and a ratchet 48 rigid with the gear 44. This construction is such that 15 a movement of the gear segment in the direction of the arrow, which will be the movement given to it by the upward movement of the head 21, will operate through the gear train to rotate the paddle 42, but a reverse 20 movement of the gear sector 41 may be accomplished without rotating the paddle, because of the pawl and ratchet connection.

The gear sector 41 is provided with a weight 49 which acts to counterbalance the 25 head 21 and stem 35, thereby providing such a construction that a relatively small decrease in pressure in the chamber 14 will raise the head 21 and stem 35.

The check valve 3 is shown as a weighted 30 valve, it being provided with a chamber filled with lead 51 and the valve seat 5 therefor is arranged at a slight inclination so as to permit a relatively rapid opening of the valve, thus reducing the friction loss as the 35 valve opens.

The operation of the device is as follows: Under normal conditions when all the 40 sprinkler heads are closed the weighted check valve 3 is closed, the auxiliary check valve 8 is also closed, the expansible chamber or bellows-like device is contracted and the wall 21 thereof is at its lowest position and the alarm valve is closed, all as shown in Fig. 1. Under these conditions there may 45 be an equilibrium of pressures above and below the check valve 3 or there may be an excess pressure above said valve, due to water having been forced through the by-pass port 6 during a temporary water surge. If a 50 sprinkler head opens or there is a flow of water from the system beyond a predetermined amount and maintained for a predetermined length of time the main valve 3 will be opened and the pressure in the chamber 14 will be reduced below that in the chamber 15. This difference in pressure 55 will cause the wall 21 of the expansible chamber to rise, such rising movement being retarded by the paddle 42. If the difference in pressure is maintained for a sufficient length of time the wall 21 will rise sufficiently to bring the pin 36 against the forked end of the lever 31 thereby lifting said lever and opening the alarm valve. The 60 opening of the alarm valve allows water to

flow through a pipe 23 to the alarm mechanism thereby to sound the alarm.

If, however, the flow of water past the check valve continues for a less time than the predetermined period, which is that required for the wall 21 to rise sufficiently to operate the alarm valve, said head will have failed during this lesser time to rise high enough to operate the alarm valve and, therefore, no alarm will be given. 75

With my device, therefore, the alarm valve will not be operated unless the flow of water past the check valve 3 is more in amount than can be accommodated through the port 6 and is maintained for a sufficient length of time to permit the wall 21 to rise to its full extent. The device, therefore, will differentiate between temporary pressure difference due to water surge and a continued pressure difference due to the giving 80 way of a sprinkler head. False alarms are thus avoided.

Another advantage of my construction is that there is no waste of water because no water will be delivered from the chamber 90 15 until the alarm valve opens and the alarm is operated.

Having fully described my invention, what I claim as new and desire to secure by Letters Patent is:

1. In an alarm valve mechanism, the combination with a water-way having a check valve therein, of a bellows-like device which is at all times subjected on its exterior to the pressure on the delivery side of the 100 check valve and on its interior to the pressure on the inlet side of the check valve, whereby said bellows will be extended when a reduction of pressure occurs on the delivery side, means to retard the expanding 105 movement of the bellows, and an alarm valve operated by the expanding movement of said bellows.

2. In an alarm valve mechanism, the combination with a water-way having a check 110 valve therein, of a bellows-like device which is at all times subjected on its exterior to the pressure on the delivery side of the check valve and on its interior to the pressure on the inlet side of the check valve, whereby said bellows will be extended when a reduction of pressure occurs on the delivery side, means to retard the expanding 115 movement of the bellows, an alarm valve, and means to operate it at a predetermined 120 point in the expanding movement of the bellows.

3. In an alarm valve mechanism, the combination with a water-way having a check 125 valve therein, of a bellows-like device subjected on one side to the pressure on the delivery side of the check valve and on the other side to the pressure on the inlet side of the check valve whereby said bellows device will be expanded when the pressure 130

on the delivery side of the check valve falls below that on the other side, an alarm valve operated by movement of said device, and means to retard the movement of said device in one direction while permitting free movement thereof in the other direction.

4. In an alarm valve mechanism, the combination with a water-way having a check valve therein, of an expansible chamber having a movable wall at all times subjected on one side to the pressure on the delivery side of the check valve and on the other side to the pressure on the inlet side of the check valve whereby said wall will be moved by pressure difference on opposite sides of the check valve, an alarm valve opened by movement of said movable wall, and means to delay the opening movement of the alarm valve until said pressure difference has existed for a predetermined length of time.

5. In a device of the class described, the combination with a water-way having a check valve therein, of two chambers, one communicating with the water-way on the delivery side of the check valve and the other communicating with the water-way on the inlet side of said check valve, a bellows-like device subjected on one side to the pressure in one chamber and on the other side to the pressure in the other chamber, an alarm valve actuated by said device when a sufficient pressure difference exists between said chambers, and means to delay the opening movement of the alarm valve until said pressure difference has existed for a predetermined length of time.

6. In a device of the class described, the combination with a water-way having a check valve therein, of two chambers, one communicating with the water-way on the delivery side of the check valve and the other communicating with the water-way

on the inlet side of said check valve, a bellows-like device subjected on one side to the pressure in one chamber and on the other side to the pressure in the other chamber, an alarm valve actuated by said device, and means to retard the valve-opening movement of said device.

7. In an alarm valve mechanism, the combination with a water-way having a check valve therein, of an expansible bellows which is at all times subjected exteriorly to the pressure on the delivery side of the check valve and interiorly to the pressure on the inlet side of said check valve, whereby said bellows will be extended when there is a reduction of pressure on the delivery side of the check valve, an alarm valve operated by the expanding movement of said bellows, and means to delay the opening movement of the alarm valve until the reduction in pressure which caused the expansion of the bellows has existed for a predetermined length of time.

8. In an alarm valve mechanism, the combination with a water-way having a check valve therein, of an expansible bellows which is at all times subjected on one side to the pressure on the delivery side of the check valve and on the other side to the pressure on the inlet side of said check valve, whereby said bellows will be operated by a difference in pressure on the opposite sides of said check valve, an alarm valve opened by the movement of said bellows, and means to delay the opening movement of said alarm valve until the pressure difference between opposite sides of the check valve has existed for a predetermined length of time.

In testimony whereof, I have signed my name to this specification.

EZRA E. CLARK.
